UNITED STATES PATENT OFFICE.

JOSHUA W. JONES AND ALBERT COOPER, OF HARRISBURG, PENNSYLVANIA.

AUTOMATIC REGISTERING INKING APPARATUS.

SPECIFICATION forming part of Letters Patent No. 295,767, dated March 25, 1884.

Application filed August 13, 1883. (No model.)

To all whom it may concern:

Be it known that we, JOSHUA W. JONES and ALBERT COOPER, citizens of the United States, both residing at Harrisburg, in the county of Dauphin and State of Pennsylvania, have invented a new and useful automatic registering inking apparatus for hand-stamps and other analogous forms for printing therewith, of which the following is such full, clear, and exact description as will, with the aid of the accompanying drawings, enable those skilled in the art to which our invention appertains to make and use it.

The principal parts and combinations of parts in our said apparatus are, first, an endless ink-distributing belt supported upon two rolls peculiarly mounted for easy removal, and held apart by elastic tension to take up the slack of the belt, and to compensate for the sag of the stretch of said belt between said rolls when operated on by the hand-stamp in inking it; second, for intercepting the sag of the stretch of said belt between said rolls, a bed or padded plate arranged between the upper and the lower stretches of said belt and mounted upon yielding supports which permit the bed to have limited vertical reciprocatory movements with such momentum that the impact of the hand-stamp, in inking it on the stretch of belt upon said bed, delays the rise of the same until an instant after said stamp is removed therefrom, and thus slurring of the ink thereon is avoided; third, actuating mechanism for driving one of the rolls supporting the endless ink-distributing belt, the same being connected with the yielding supports of said bed and impelled by its reciprocatory movements; fourth, actuating mechanism, likewise connecting with the yielding supports of said bed, for driving the registering-indices, to indicate thereby the number of articles stamped; fifth, an ink-fountain having rollers contiguously arranged with said belt and propelled by it for distributing ink thereon, and having an adjustable connector for regulating the supply of the ink; sixth, several combinations of the coacting parts.

In the further description reference is had to the accompanying drawings, in which Figure 1 represents a perspective view of our complete apparatus. Fig. 2 represents a longitudinal vertical section of our said apparatus,

taken near the middle of it. Fig. 3 represents a bottom view of our improved bed, with its holders for securing the pad thereon. Fig. 4 represents a perspective view of our ink-fountain detached. Fig. 5 represents a sectional view of the casing, showing the levers, springs, bands, pawls, ratchets, and stops therein. Figs. 6 and 7 represent plans of the levers on which the bed is supported. Fig. 8 represents an interior elevation of one of the two similar sides of the casing. Fig. 9 represents a front transverse view of the casing and the yielding tension-roll. Fig. 10 represents a transverse view of the rear end of the casing, and shows the unyielding belt-roll, with ratchets, shields, and pivoted levers. Fig. 11 represents a transverse view of our apparatus, taken through the axis of the drive-shaft of the registering device.

In the description similar reference-letters denote similar parts throughout the several views.

Letter A denotes the sides of the casing. 75
g g' are lugs for attaching them to base B.

A² denotes open-hooked bearings for the journals Y' of the yielding roll Q.

Letter r denotes pins on sides A, for attaching the rubber bands N thereon, which embrace sleeves p on the journals Y', to protect said bands against wear and to lessen the friction at said journals. By this means the roll Q is permitted to yield or sway from its bearings when the endless ink-distributing belt R is acted upon by blows from the hand-stamp while being inked thereon in the usual way. The bed L, supported between the stretches of said endless belt, also sways or moves under said blows. These vertical movements are utilized to propel mechanism by which said endless ink-distributing belt or expanse is intermittently moved to present freshly-inked portions thereof to the said hand-stamp, and by which the ink-rollers and the registering adjuncts or mechanisms are also automatically operated, as hereinafter set forth.

F' denotes open bearings for the journals Y of the roll P, which is kept to its bearings partly by tension of the belt R, derived from the bands N or their equivalents, connecting the roll Q to its bearings, and partly by pressure of the distributing-roller V, caused by the tension of the elastic connector N', which

holds the ink-fountain adjustably to place. Said bands N may be detached from their supporting-pins r, and the rolls Q and P may then be removed from their bearings. The 5 bed L is, however, first removed by simply lifting it from its supports M M' and out of the guide-ways A³ A⁴, it having guides F thereon for traversing and being guided by said ways. Said bed L is laterally guided, 10 when in place, by the tympan-holders f f' f² thereon abutting against the sides A of the casing. Said bed L is recessed on top, to rightly support the blanket R² thereon, which latter is felt, leather, rubber, or other suitable 15 material. Said bed is recessed more deeply underneath, to present sufficient flange extent to form in it slots x, for inserting through them the limbs f of the tympan-holders f f' f², the same being coupled together, after insertion, 20 by the rubber bands O' or their equivalents, in such manner that the loops f² thereof may bear by the tension of the bands against the ends of the bed, and hold between said ends and loops f² the tympan R', stretched over the 25 blanket R², as shown in Figs. 1 and 2. The ledges f' on the ends of the bed serve as catches to keep the said loops f² down in clasped position, and the guides F thereon limit the throw of the said holders. The bed 30 thus made and equipped can be readily inserted to place between the stretches of the belt or removed for repairs, as set forth.

When the bed L is in its place, the guides F thereon rest on the pivoted levers M M' at 35 points l l'. Said levers are pivoted at D' and D, respectively, about equally distant from the sliding joints made by rivets J' and slots D' at their deflectable ends, that they may have a like and simultaneous movement when 40 the bed L thereon is pressed upon at any edge, corner, or the middle thereof, the said levers being upheld interiorly solely by the springs U. Said levers are limited in their descent by rubber blocks h, to stop them noiselessly. 45 The stops h' arrest their movement upward. These limitations operate to enable the ratchets to act certainly in connection with their respective pawls, especially pawls k on ratchets K. The bed L is supported widely on said 50 levers by the guides F, resting thereon. Said bed is therefore not liable to tilt or become disarranged if it is carelessly struck upon in inking the hand-stamp.

The registering device proper consists of 55 the pawls k, pivoted one to each of the levers M', ratchets K—one on each end of the shaft K'—and any suitable indices or wheels, a b c d e, arranged on the outside of the casing, as shown in Figs. 1 and 11. The ratchets K have 60 their teeth arranged to stand intermediately or staggered in relation to each other, to secure certain catching by the pawls k every time the hand-stamp is thrust on the bed L. The above staggered arrangement of the teeth 65 of the one ratchet K, to stand intermediately in relation to the teeth on the other ratchet K on the opposite end of said shaft K', in effect

doubles the number of teeth in each, since if one of two similar pawls, k', does not catch on the one ratchet, the other pawl is sure to catch 70 on a tooth of the other ratchet. Thus light strokes by the stamp in inking it, as stated, will not fail to rotate the registering mechanism the requisite number of degrees to be recordable by the indicators. The instant after 75 said stamp is removed from said bed and belt R thereon, the springs U elevate the levers M M', and not before, owing to the inertia and a degree of lost motion of the coacting parts, thus gaining a moment's advance start of said 80 removal, and hence avoiding slurring of the ink on said stamp. The pawls k' then move the ratchets Z on roll P, and it drives or propels the belt R, and by its contact the roller V, which moves roller W, thus resuming the drawing of ink from the ink-fountain by the duck-roller W, and the distributing of a regulated portion of it, by the distributing-roller V, onto the said belt automatically after each inking of the hand-stamp on said belt. Thus continuously freshly-inked portions of said belt will be 85 brought forward to be presented to said stamp. Said roll P has a knob, T, on its extended journal Y, which knob may be handled to perfectly distribute ink on said belt R if it is not 90 in right condition to resume the operation of stamping after an interval of rest. The registering device will not be disturbed in this way of replenishing said belt, as its record indicates merely the times the bed is vibrated or thrust 95 upon by the stamp. Both the sets of pawls k' are held engaged with their respective ratchets K Z by one embracing rubber band, N'; but evidently each pawl may have its own tension device applied separately to it with 100 the same result. The ink-fountain has inside 105 of its ends S² the slant ways V' W', in which the rollers W V are removably journaled in such manner that the distributing-roller V rides on the duck-roller W and derives its 110 supply of ink therefrom. The ink-fountain is cut away in front at S', that the belt R may 115 freely pass over it when it is located as shown in Fig. 1. Our ink-fountain S S' W V is removably placed in the casing A B, and has 120 the distributing-roller V arranged contiguously with the endless ink-distributing belt R, and so that the axis of said roller V is parallel with the axis of the roll P, supporting said belt, which latter and said roller are kept together adjustably by the elastic connector N', 125 applied in the cuts E E', or in an equivalent manner, which connector bears against a part, S, of said fountain, and by its tension presses it forward. By altering the position of said 130 connector in said cuts, said tension may be increased or diminished at pleasure, and thereby the supply of the ink distributed can be regulated, the roller V distributing or permitting a greater supply to pass to said endless belt R the less said tension is, and vice versa.

Our said endless ink-distributing belt R may be made in sections or as a whole, and of any

suitable material, as of rubber, leather, buck-skin, textile fabric, felt, or even sheet metal.

Our said ink-fountain may be located above, to the rear, or nearly beneath said roll P, and 5 a series of distributing-rollers, V, may be employed to effect perfect distribution of the ink.

Our said registering device may be omitted in part or as a whole.

A suitable cover may be added to the casing to exclude dust from the fountain and other portions of it.

What we claim is—

1. In an apparatus for inking hand-stamps and other analogous forms, an endless ink-distributing belt, in combination with bed having reciprocatory vertical movements arranged between stretches of said belt, and actuated by mechanism, substantially as described, by 15 blows of an independent hand-stamp while inking it, to present successive portions of said belt freshly inked automatically from an ink-fountain, substantially as set forth.

2. In an apparatus for inking hand-stamps and other analogous forms, the combination of 25 an endless ink-distributing belt, suspended upon rolls whose distance apart is regulated by elastic tension, a bed supported between stretches of said belt, upheld and guided to permit it to have vertical reciprocatory movements in sustaining the blows from a hand-stamp, and mechanism, substantially as described, connecting said bed and rolls, for propelling said belt automatically, driven by said imparted blows in inking said stamp, substantially as set forth.

3. In an apparatus for inking hand-stamps and other analogous forms, an endless ink-distributing belt, in combination with mechanism, substantially as described, for moving it automatically by the impulses of a hand-stamp in inking the same on said belt, with the mechanism set forth registering the number of said impulses, and with mechanism, substantially as described, connecting the belt-moving mechanism with the registering mechanism, substantially as herein set forth.

4. The endless ink-distributing belt R and the reciprocating bed L, in combination with the drive-roll P, the yielding stretcher-roll 50 Q, the bands N, and sleeves p, applied to the journals Y' of the latter roll, for holding the same, thereby to give compensative tension to said belt or belt-surface, and permit portions of it and the bed L, inclosed between stretchers of it, to move vertically without overstraining said belt, substantially as and for the purposes set forth.

5. The reciprocatory pivoted levers M', having the pawls k', pivoted thereto and united 60 by the slip-joints J' D' to the co-operating levers M, pivoted likewise to the sides A, in combination with the supporting-springs U, under said levers, the equipped bed L R' E', the belt R, the rolls Q P, the ratchets Z on the latter, and stops h h', all arranged and co-operating to convert the reciprocatory vertical movements of said bed derived from impulses

of a hand-stamp into rotary motion, for propelling said belt or belt-surface automatically, substantially as set forth.

6. The reciprocatory pivoted levers M M', connected in operation by the joints J' D', and connected by pawls k k' thereon with the ratchets Z on the drive-roll P, and with the staggered ratchets K, in combination with the reciprocatory equipped bed L R' R², the belt R, the yielding roll Q, the limiting-stops h h' on sides A, and shaft K', with indices, all arranged and operating to propel both said endless belt and registering device automatically 80 and alternately, as set forth.

7. The combination of the bed L, with guides F thereon, and pad R' R², the reciprocatory supports M M', the pawls k', the stops h h', the springs U, the inking-belt R, the rolls Q P, 85 the ratchet Z on the latter, all arranged in and on casing A B, and certainly coacting to propel said belt only the instant after the hand-stamp giving it impetus to move is withdrawn therefrom, substantially as set forth.

8. The combination of the bed L, having 90 slots X in flanges thereon below and ledges f³ on its ends, the tympan-holders f f' f², having their limbs f' united by bands O', the blanket R², and tympan R', secured on said bed, in the manner herein set forth, for the purpose specified.

9. The combination of the endless ink-distributing belt or belt-surface R, the ink fountain or vessel S S', the duck-roller W, the distributing-roller V, and the adjustable band N', all co-operating to automatically maintain the supply of ink on said belt and to regulate the quantity distributing thereon, substantially as set forth.

10. The combination of the endless ink-distributing belt R, with the rolls P Q, with the ink-fountain S S', its rollers W V, and regulating elastic connector N', with the bed L, equipped with blanket R², tympan R', tympan-holders f f' f², and bands O', and supported on the levers M M' and springs U, and with ratchets Z and pawls k' on the said levers, which latter are duly limited in their movements, all co-operating to propel said belt and keep ink perfectly distributed thereon automatically, as and for the purpose set forth.

11. The combination of the endless ink-distributing belt R, mounted compensatingly for stretching or contracting on rolls P Q, of variable distance apart, the ink-fountain S S', with rollers W V therein, connected by band N' of adjustable tension, to regulate the supply of ink on said belt, the equipped bed L R' R² f f' f², the supports M M' U h h', ratchets K Z, pawls k k', shaft K', and registering-indices, all mounted and co-operating as and for the purposes set forth.

JOSHUA W. JONES.
ALBERT COOPER.
